UNITED STATES PATENT OFFICE.

JAMES S. HAGGERTY, OF MANNINGTON, WEST VIRGINIA.

TOBACCO BUNCHING AND ROLLING MACHINE.

1,239,003.

Specification of Letters Patent.

Patented Sept. 4, 1917.

Application filed September 18, 1916. Serial No. 120,776.

To all whom it may concern:

Be it known that I, JAMES S. HAGGERTY, a citizen of the United States, residing at Mannington, in the county of Marion and 5 State of West Virginia, have invented certain new and useful Improvements in Tobacco Bunching and Rolling Machines, of which the following is a specification.

This invention relates to cigar and stogy 10 bunching and rolling machines.

It is the aim of this invention to provide an elastic tobacco bunch receiving pocket, which will automatically adjust itself to the size of bunch or filler for properly rolling 15 the latter.

Another object of the invention is to simplify the general structure of the invention and to provide a smooth operation of the device for reducing the cost of manufacture to a minimum, and to increase the 20 output of each machine.

A further object of the invention is to house the mechanism by which the drum may be operated within the latter, so as to 25 prevent contact of the operator therewith and also to maintain said mechanism in an inconspicuous place.

Referring to the drawings:

Figure 1 is a sectional view of the device 30 showing the complete operating mechanism in side elevation.

Fig. 2 is a top plan fragmentary sectional view of the machine, the apron and belt being removed from the drum to disclose 35 details.

Fig. 3 is a sectional view taken through the complete machine, and

Fig. 4 is a fragmentary front elevational view of the machine.

40 In the drawings a table 1 is provided which has an opening formed in the top thereof through which a drum 2 operates, the latter being mounted upon an axle 3. The axle 3 is journaled in suitable bearings 45 on the table top and has mounted thereon, within said drum 2, a ratchet wheel 4. Said ratchet wheel is in fixed engagement with the drum 2, so as to be simultaneously operated with the latter.

50 A standard 5 is depended from the bottom of the table 2, the upper end of said standard being pivoted to the table top, while the opposite end is equipped with a foot engaging portion 6, whereby the stand- 55 ard may be rocked on its axis. A link 7 is

provided, one end of which is in pivotal engagement with the standard 5 and the opposite end offset and pivotally engaged with one end of a link 8. The link 8 is pivotally mounted upon the axle 3 and completely housed within the drum 2, a pawl 9 being pivotally mounted in its free end. The pawl 9 as shown to advantage in Figs. 1 and 3 normally gravitates into engagement with the ratchet wheel 4, whereby 60 when the standard 5 is operated in a direction toward the rear of the machine, the pawl will engage the teeth of the ratchet wheel and rotate the same, thereby imparting movement to the drum 2. 70

A belt 10 is engaged with the drum 2 in the usual manner and has superposed thereupon an endless apron 11. The apron 11 is engaged with a carriage 12 at the rear of the machine, the latter being slidably 75 mounted upon horizontal parallelly arranged rods 13 which are carried by the table top. The carriage 12 is normally held in close proximity to the rear of the table by spiral springs 14, the inner convolution 80 of each of which is engaged with the carriage, while the outermost convolution of each of said springs is engaged in the eye of an adjustable eye bolt 15. A thumb nut 16 is engaged with each eye bolt, whereby 85 the tension of said springs 14 may be adjusted. The apron 11 is trained about a roller 17 which is depended from the bottom of a smoothing plate 18, the latter being slidably mounted upon the rods 13 and being 90 normally held in close proximity to said drum 2 by spiral springs 19, each of the latter having one end thereof engaged with a portion of the smoothing plate, while the opposite end of each is in engagement with 95 ears 20 which are projected laterally from sleeves 21. The sleeves 21 are independent 100 of the smoothing plates and are slidably mounted upon the rods 13, but are held in any predetermined position by a set screw 22. 100

From the above it will no doubt be obvious that the apron 11 is normally distended, but is flexible under pressure in order to form a pocket, as indicated at 23, and shown to advantage in Fig. 3. The springs 105 14 are adapted to be so adjusted that a very small pocket will normally be provided, in order to require the exertion of pressure thereon in order to expand the pocket, the pocket in this way always adjusting itself 110

to snugly engage the tobacco bunch or filler immaterial of the size of the latter. As will no doubt be understood the filler will always be composite, and will be thoroughly 5 rolled upon rotation of the drum 2.

It will be understood that the above description and accompanying drawings comprehend only the general and preferred embodiment of my invention and that various 10 minor changes in details of construction, proportion and arrangement of parts may be made within the scope of the appended 15 claims without sacrificing any of the advantages of my invention.

15 I claim:—

1. A tobacco bunching and rolling machine including a table, a drum in said table, mechanism arranged in said drum whereby the latter may be operated, an apron trained 20 about said drum to receive the tobacco and the latter being rolled by movement of the drum, and a foot operating member depending from said table and in connection with the operating mechanism for actuating the 25 latter.

2. A tobacco bunching and rolling machine including a table equipped with a rotatable drum, an apron trained about said drum, a smoothing plate structure slidably 30 mounted on the table and having a portion thereof engaged with said apron, means slidably mounted on the table and co-acting with said smoothing plate structure to permit flexure of the apron between said means and 35 said smoothing plate structure, and springs

connecting said means and smoothing plate structure.

3. A tobacco bunching and rolling machine including a table equipped with a movable member, an apron trained about said 40 member, a smoothing plate structure slidably mounted on the table and having a portion thereof engaged with said apron, sleeves slidably mounted on the table and equipped with a roller adjacent the smoothing plate, 45 and means to hold said sleeves and smoothing plate structure together.

4. A tobacco bunching and rolling machine including a table equipped with an axle, a drum mounted on said axle, a ratchet 50 wheel arranged within said drum and movable therewith, means in engagement with said ratchet wheel to operate the latter for imparting movement to said drum, and a belt carried by said drum and operable by 55 movement of the latter to roll tobacco carried upon said belt.

5. A tobacco bunching and rolling machine including a table, a drum mounted in said table, mechanism arranged within said 60 drum whereby the latter may be operated, and an apron trained about said drum to receive tobacco, said tobacco being rolled in the apron by movement of said drum.

In testimony whereof I affix my signature 65 in presence of a witness.

JAMES S. HAGGERTY.

Witness:

M. E. JONES.
